UNITED STATES PATENT OFFICE.

ALMA V. HENDLEY, OF KANSAS CITY, MISSOURI.

DESIGN FOR A STATUETTE.

Application filed February 2, 1923. Serial No. 5,057. Term of patent 3½ years.

To all whom it may concern:

Be it known that I, ALMA V. HENDLEY, a citizen of the United States, residing at Kansas City, Jackson County, Missouri, have invented a new, original, and ornamental Design for Statuette, of which the following is a specification, reference being had to the accompanying drawing, forming part thereof.

In the drawing:

Fig. 1 is a front perspective view of a statuette showing my new design.

Fig. 2 is a side view of the same.

I claim:

The ornamental design for a statuette as shown.

ALMA V. HENDLEY.
